Louis Hornberger INVENTOR

BY *Geo. L. Cooper*

ATTORNEY

UNITED STATES PATENT OFFICE.

LOUIS HORNBERGER, OF BRIDGEPORT, ASSIGNOR TO THE EDWARD MILLER & COMPANY, OF MERIDEN, CONNECTICUT.

DESIGN FOR A BASE FOR LAMPS.

SPECIFICATION forming part of Design No. 25,144, dated February 11, 1896.

Application filed December 21, 1895. Serial No. 572,957. Term of patent 3½ years.

To all whom it may concern:

Be it known that I, LOUIS HORNBERGER, a citizen of the United States, residing at Bridgeport, Fairfield county, Connecticut, 5 have invented a new Design for Bases for Lamps and the Like, of which the following is a specification.

The accompanying drawings represent my base, Figure 1 in perspective, and on a smaller 10 scale, Fig. 2, in top plan view.

The invention relates to a design for a base adapted to lamps and other articles; and the design consists in the configuration and ornamentation thereof, as shown in the illustrations. 15

The base consists of four feet attached to a low irregularly conical body, the outer portion of which is of open-scroll and lattice work. Above and within this outer portion 20 is a plain concave member surrounding an inner concave portion ornamented with alter-

nate radial raised ribs and rows of bead-like projections. The feet are surmounted by irregular medallions and are ornamented by scrolls. Two opposite feet project radially 25 from the body of the base, the alternate two feet being curved from a radial line.

The leading feature of the design is the outer convex open-work portion, the concave center portion with raised ribs and bead-like 30 rows, and the feet, two of which oppositely placed differ from the other two in being curved from a radial line.

What I claim as my invention, and desire to secure by Letters Patent of the United 35 States, is as follows:

The design for a base for lamps, herein shown and described.

LOUIS HORNBERGER.
